(57) **CLAIM**

The ornamental design for absorbent article or package with surface indicia, as shown and described.

DESCRIPTION

FIG. 1 is a perspective view of an absorbent article or package with surface indicia showing my new design;

FIG. 2 is a top view of the absorbent article or package with surface indicia as shown in FIG. 1;

FIG. 3 is a bottom view of the absorbent article or package with surface indicia as shown in FIG. 1;

FIG. 4 is a right side view of the absorbent article or package with surface indicia as shown in FIG. 1;

FIG. 5 is a left side view of the absorbent article or package with surface indicia as shown in FIG. 1;

FIG. 6 is a front side view of the absorbent article or package with surface indicia as shown in FIG. 1; and,

FIG. 7 is a back side view of the absorbent article or package with surface indicia as shown in FIG. 1.

The broken lines surrounding the design designate a single repeat unit of absorbent article or package with surface indicia and indicate that a specific length and width forms no part of the claimed design and that the design as shown can repeat uniformly as shown throughout the surface of the absorbent article or package. The broken lines form no part of the claimed design.

The dotted lines within the design are part of the absorbent article or package with surface indicia and do form a part of the claimed design.
